BUCKLE

Paul W. White, Chicago, Ill., assignor to Parva Products Company, Chicago, Ill., a corporation of Delaware

Application March 25, 1933, Serial No. 662,691

4 Claims. (Cl. 24—73)

This invention relates to a buckle and has special reference to a buckle formed of wire for use in the supporting of garments, and the like.

More particularly, this invention relates to a buckle comprising a frame having a button engaging portion and a strap engaging portion, the frame being formed of a single continuous wire with either an integrally or detachably formed end supporting portion.

10. The construction of the buckle is such that a strap or the like in being threaded therethrough will act to prevent accidental disengagement of the button from the button engaging portion thereof and the strap engaging portion of the buckle is preferably such as to effect a transverse distortion of the strap against the direction of pull when the buckle is in use to prevent slippage of the strap relatively to the buckle.

15. Hereinafter the device will be described as is shown in the drawing, that is, in connection with a button attached to the front bib of an overall or other garment for detachable connection with the shoulder straps thereof. In a buckle of the above type, it is contemplated that an efficient and practical article may be produced at a minimum cost. The construction of the buckle specifically contemplates the formation of the intermediate portion of the single continuous wire into an outer substantially rectangular frame, the end portions of the wire being formed into cross-bars spaced from the outer frame and connected to one side thereof to define transverse slots for receiving a strap or the like. The cross-bars intermediate the frame of the buckle likewise occupy a spaced relation in defining a transverse slot therebetween, which space is gapped at one side of the frame either by a separately formed collar or similar connection or by providing integrally formed extensions which may preferably be welded or otherwise secured together.

20. The lower side of the frame is provided with a looped portion preferably opening into one of the transverse slots to be engaged by a button and the adjacent cross-bar is provided preferably with spaced offset portions for engaging the line of fold of a strap threaded through the transverse openings to substantially close said loop and to effect a distortion of the strap against the direction of pull when the buckle is in use so as to prevent relative slippage therebetween. One of the objects of this invention is to provide a buckle of the character above noted which is simple in construction, comparatively inexpensive to manufacture, and efficient in operation.

25. Another object of this invention is to provide a buckle of the type above pointed out which may be formed of a single length of wire in its entirety or substantially so.

30. Other objects and advantages will hereinafter be more particularly pointed out and for a more complete understanding of the characteristic features of this invention, reference may now be had to the following description when taken together with the accompanying drawing, in which latter:

35. Figure 1 is a face view of a buckle constructed in accordance with the teachings of this invention;

40. Fig. 2 is a central vertical sectional view taken on the line 2—2 of Figure 1, showing a strap in full lines threaded on the buckle;

45. Fig. 3 is a view similar to Fig. 2 taken on the line 3—3 of Figure 1, showing the strap as omitted therefrom;

50. Fig. 4 is a face view of a buckle incorporating a modified form of construction in accordance with the teachings of this invention, showing a button in dotted lines;

55. Fig. 5 is a view similar to Figure 1, showing a modified form of construction for bridging the space between the intermediate bars; and

60. Fig. 6 is a fragmentary elevational view partially in section, showing a still further modification of the manner of bridging the space between the intermediate bars.

65. Referring now to the drawing and more particularly to Figs. 1 to 3 thereof, the buckle is shown as comprising a frame designated generally by the reference character 10. The frame is preferably substantially rectangular in shape and comprises a single continuous wire, the portion intermediate the ends of which comprise the outer frame of the buckle and the end portions of which comprise cross-bars intersecting the frame member and dividing the same into transverse slots.

70. The buckle may be conveniently formed on the usual wire forming machine of standard make commonly termed "multiple slide", or, in the present instance, "four-slide machines". Such machines consecutively and continuously bend the wire in its various directions. As shown in the drawing, an intermediate portion of the wire forms a side 11 of the frame and one adjacent portion thereof is bent substantially at right angles thereto to form an upper side 12, the continuation of this side being bent back in an opposite direction and at a spaced distance therefrom to form an intermediate bar 13. The adj-

cent portion of the wire extending from the side 11 is bent at right angles thereto to form a lower side 14 having a looped central portion 15, the extreme end thereof being bent back in the opposite direction to form a second intermediate bar 16. The extreme outer ends of the intermediate bars 13 and 16 are preferably fixedly attached to the side frame 11 as by means of welding, soldering, or clamping the ends thereabout as at 17. 5 The intermediate bars 13 and 16 are spaced from the upper and lower sides of the frame members 12 and 14, respectively, and are likewise spaced relatively to each other, thus forming an upper slot 18, a lower slot 19, and an intermediate slot 20 for receiving the strap as it is threaded in the manner hereinafter specified. 10

In the formation of the buckle, as above recited, the slot 20 is not enclosed at one end and, therefore, in order to enclose the same and to support 20 the adjacent portions of the buckle at that end, a connection 21 is provided comprising preferably a shell of substantially annular cross section, the upper end 22 of which snugly engages the circumference of the wire at the point of bend between 25 the portions 12 and 13, and the lower end 23 of the shell engages the circumference of the wire at the bend between the portions 16 and 14. The intermediate portion 24 of the shell acts as a spacer between the adjacent wires and also to 30 strengthen the construction of the shell. The upper, lower and intermediate portions of the shell are provided with openings or cutaway portions through which the portions of the wire may extend. 35

The cross-bar or intermediate bar 16 positioned adjacent the side 14 of the buckle frame is provided with a pair of spaced offset portions 25 and 26, which latter form a depressed portion 27 therebetween, the latter being opposite the opening into 40 the loop 15. Thus, the lower slot between the lower frame portion 14 and the intermediate bar 16 is relatively wide opposite the opening into the loop and, as will hereinafter be more particularly pointed out, when associated with the strap, will 45 act to prevent accidental disengagement of the button from the loop.

A strap 28 is shown as being threadedly engaged with the buckle in the following manner:

The strap passes downwardly to the rear of the 50 upper side 12 of the frame and then forwardly through the slot 18 over the bars 13 and 16 and rearwardly through the transverse slot 19. The strap is then passed upwardly and forwardly through the transverse slot 20 and then rearwardly and upwardly through the transverse slot 18, the free end 29 of the strap being disposed in the rear of the body portion of the strap and thus behind the buckle. 55

It will be noted that when the strap is thus 60 threadedly engaged with the buckle the line of fold 30 of the strap is positioned adjacent the opening into the loop 15 and thus substantially closes this opening since the head of the button is substantially greater than the diameter of the 65 loop. It will be noted further that the offset portions 25 and 26 engage the strap at the line of fold thereof so that a relative pull between the strap and buckle is exerted on the strap and buckle at the points of engagement of the offset 70 portions of the bar 16 with the strap. This arrangement of the strap relatively to the buckle effects a transverse distortion of the strap against the direction of pull when the buckle is in use so as to prevent slippage of the strap relatively to 75 the buckle.

In use a strap will be threadedly engaged with the buckle in the manner previously described and a button attached to the bib of an overall or the like will be engaged with the loop 15. As long as there is a relative pull between the strap and button, the button will remain in the position shown in Fig. 2 of the drawing, or, in other words, in the lower end of the opening into the loop 15. If, however, this relative pull should be relieved and the button should slip upwardly in the loop, 10 it can not become disengaged from the buckle owing to the strap extending across the raised offset portions 25 and 26, which latter substantially close the opening into the loop when the strap is extended thereover. Thus the button 15 may not become accidentally disengaged from the button loop 15.

When, however, it is desired to disengage the button from the loop, the button may be tilted to engage the edge thereof with the adjacent folded portion of the strap forcing such folded portion into the recess 27 between the offset portions 25 and 26, thus allowing the passage of the button through the slot by reason of the resiliency of the material of the strap to a disengaged position. 25

It is thus to be noted that the line of fold of the strap being positioned as it is adjacent the outlet opening of the button-receiving loop constitutes a means for yieldably maintaining the 30 button in engagement with the loop and it becomes necessary to displace the adjacent folded portion of the strap to effect disengagement of the button from the loop with the result that the folded portion of the strap constitutes in effect 35 a resilient or compressible cushion for maintaining the button in engaged position. The bar 16 having the recessed portion 27 therein conforms substantially to the curvature of the edge of the button adapted to be engaged in the buckle loop 40 and as the folded portion of the strap is forced into the recessed portion, there is sufficient clearance to permit the passage of the button rearwardly through the slot 19 and thus to disengaged position. Further, the offset portions engaging 45 the line of fold of the strap prevent the side edge of the strap from slipping inwardly toward the center of the bar 16 to hold the strap under tension between the offset portions of the bar.

Referring now more particularly to Fig. 4, the 50 construction of the buckle thereof is slightly modified in the provision of offset portions 31 and 32 formed in the lower bar 14 adjacent the loop opening and extending into the lower slot 19 for cooperation with the offset portions 25 and 26. 55 Also the outer ends 17A of the intermediate bars 13 and 16 are shown as being flattened to engage fixedly flattened portions of the intermediate portion 11 of the frame, there being a collar 21A similar to the collar on the opposite side of the 60 frame to make the buckle symmetrical and to strengthen the constructions. This construction may be used alternatively on the various modifications herein shown. 65

The offset portions 31 and 32 are preferably spaced outside of the offset portions of the bar 16 and they preferably terminate in substantially the same lateral plane therewith. Thus, for example, in the preferred construction shown in 70 Fig. 4, a straight line drawn transversely of the buckle will touch the peaks or outermost points of each of the offset portions, and, as shown in the drawing in dotted lines, a portion of any thickness at all in order to be threaded through 75

the slot 19 will actually be distorted in any condition of use.

The threading of the strap through the buckle and the general construction of the buckle is the same as that described with reference to Figs. 1 to 3, inclusive, and a further description thereof would make this specification unnecessarily prolix. The same description may, therefore, be employed and the same numerals have been transferred to make the same easily readable.

The construction shown more particularly in Fig. 5, to which attention is now directed, contemplates the employment of an all-wire frame wherein the intermediate bars are provided with offset portions, which latter are fixedly joined together to form one side of the frame and to enclose the intermediate slot. The wire is bent in substantially the same manner as in Figure 1, there being an intermediate portion of the wire having the adjacent portions thereof bent at right angles thereto with the end portions extending from the adjacent portions into the frame to form intermediate bars. However, offset portions 33 and 34 are provided in the wire at the points of extension of the intermediate bars from the upper and lower bars and, as shown in the drawing, are preferably welded or soldered together. It is to be understood, however, that instead of having two offset portions meeting substantially centrally, as shown in the drawing, only one offset portion need be provided at the point of extension of one of said intermediate bars with either the upper or lower bar to extend across and bridge the entire gap of the intermediate slot 20.

Instead of soldering or welding the offset portions 33 and 34 together, as shown in Fig. 5, it may be desirable to provide a separate connection, such as the collar 35 shown more particularly in Fig. 6. This connecting member is preferably in the form of a metal band which snugly engages the periphery of each of the offset portions or is held thereto by any suitable fastening means.

A device built in accordance with the above instructions may be very simple in construction, comparatively inexpensive to manufacture, and efficient in operation. A wire of but a single continuous piece with but a simple connection employed therewith makes for simplicity in construction and inexpensiveness to manufacture. The buckle is very efficient in operation since a button is held against displacement by the resilient cushioning means formed by reason of the strap being threaded in a manner to present a line of fold across the offset portions. The strap is held securely against slippage by reason of these blunt offset portions and further, as shown in one modification, by cooperating offset portions.

While several embodiments of this invention are herein shown and described, it is to be understood that various modifications thereof may be apparent to those skilled in the art without departing from the spirit and scope of this invention and, therefore, the same are only to be limited by the scope of the prior art and the appended claims.

I claim:

1. A buckle of the character described comprising a frame constructed from a continuous wire having an intermediate portion forming one side

of said frame with adjacent portions thereof extending therefrom to form upper and lower bars of said frame and the end portions extending from said upper and lower bars into said frame to form intermediate bars dividing said frame into upper, lower and intermediate slots, and a substantially cylindrical shell having end and intermediate spaced openings for passage of said wire at the points of extension of said intermediate bars from said upper and lower bars to form the other side of said frame.

2. A buckle of the character described for association with a flexible strap comprising a single continuous wire formed to define a frame having upper, lower and side bars, and intermediate bars extending between said upper and lower bars for providing upper, lower and intermediate slots, said lower bar having an outwardly extending loop opening into said lower slot for retaining a button, the lower of said intermediate bars having spaced offset portions extending in the direction of said lower slot, and said lower bar having offset portions adjacent said loop-opening extending into said lower slot for cooperation with said offset portions in said intermediate bars in engaging the strap to substantially close said loop to prevent accidental displacement of said button therefrom unless manually forced and to provide a transverse distortion of said strap against the direction of pull.

3. A buckle of the character described for association with a flexible strap comprising a single continuous wire formed to define a frame having upper, lower and side bars, and intermediate bars extending between said upper and lower bars for providing upper, lower and intermediate slots, said lower bar having an outwardly extending loop opening into said lower slot for retaining a button, the lower of said intermediate bars having spaced offset portions extending in the direction of said lower slot, and said lower bar having offset portions adjacent said loop-opening extending into said lower slot outside of and for cooperation with said offset portions in said intermediate bars in engaging the strap to substantially close said loop to prevent accidental displacement of said button therefrom unless manually forced and to provide a transverse distortion of said strap against the direction of pull.

4. A buckle of the character described for association with a flexible strap comprising a single continuous wire formed to define a frame having upper, lower and side bars, and intermediate bars extending between said upper and lower bars for providing upper, lower and intermediate slots, said lower bar having an outwardly extending loop opening into said lower slot for retaining a button, the lower of said intermediate bars having spaced offset portions extending in the direction of said lower slot, and said lower bar having offset portions adjacent said loop-opening extending into said lower slot terminating in substantially the same lateral plane outside of and for cooperation with said offset portions in said intermediate bars in engaging the strap to substantially close said loop to prevent accidental displacement of said button therefrom unless manually forced and to provide a transverse distortion of said strap against the direction of pull.
